WINDOW REGULATOR

Andrew J. Campbell, 25125 Stonycroft, Southfield, Mich.

Filed May 4, 1964, Ser. No. 79,807

Term of patent 14 years

(Cl. D10—10)

FIG. 1 is a front elevational view of a window regulator embodying my new design; and

FIG. 2 is an end elevational view taken at the right hand end of FIG. 1; and

FIG. 3 is a rear elevational view; and

FIG. 4 is an end elevational view taken at the right hand end of FIG. 3; and

FIG. 5 is a top plan view thereof; and

FIG. 6 is a bottom plan view thereof.

I claim:

The ornamental design for a window regulator, substantially as shown.
